DESIGN FOR A CAP FOR LIQUID DISPENSING BOTTLE

Charles T. Gerhart, Cincinnati, Ohio, assignor to
The Procter & Gamble Company, Cincinnati,
Ohio, a corporation of Ohio

Application June 12, 1939, Serial No. 85,458

Term of patent 14 years

To all whom it may concern:

Be it known that I, Charles T. Gerhart, a citizen of the United States and a resident of Cincinnati, in the county of Hamilton and State of Ohio, have invented a new, original, and ornamental Design for a Cap for Liquid Dispensing Bottle, of which the following is a specification, reference being had to the accompanying drawing forming a part thereof.

In the drawing:

Fig. 1 is a top plan view of the cap for a liquid dispensing bottle showing my new design;

Fig. 2 is a side elevational view; and

Fig. 3 is a perspective view thereof.

I claim:

The ornamental design for a cap for liquid dispensing bottle, substantially as shown.

CHARLES T. GERHART.
